CLAIM

The ornamental design for a baby monitor camera, as shown and described.

DESCRIPTION

FIG. 1 is a top, front, right isometric view of a baby monitor camera showing our new design;

FIG. 2 is a top, rear, right isometric view thereof;

FIG. 3 is a front elevation view thereof;

FIG. 4 is a rear elevation view thereof;

FIG. 5 is right side elevation view thereof;

FIG. 6 is a left side elevation view thereof;

FIG. 7 is a top plan view thereof; and,

(Continued)

FIG. 8 is a bottom plan view thereof.

The broken lines shown in the drawings depict portions of the baby monitor camera that form no part of the claimed design.
